UNITED STATES PATENT OFFICE.

LEWIS W. PARSONS, OF SHIRLEY, MASSACHUSETTS.

COMBINED CHAIR AND COUCH.

Application filed September 18, 1924. Serial No. 738,472.

This invention relates to household furniture and more particularly to combined chairs and couches.

The object of the invention is to provide a combined chair and couch the parts of which are so constructed and connected that on the releasing of a lever the occupant may by gently leaning back cause the back of the chair to move downward and an apron or foot rest at the front to simultaneously rise and when these members reach the desired angle when the motion may be checked and the parts locked by dropping the lever which is engaged and held when so dropped until again manually released.

Another object is to so construct an article that when opened to its full extent will form a couch firmly supported by six legs.

Another object is to so construct such an article of this character that the legs and foot rest may be raised and lowered in unison with or independently of the back.

Another object is to provide a chair of this character equipped with rear extension legs so hung that they will support the back of the chair at any point.

Still another object is to provide an article of this character in which the back, seat, arms, foot rest, automatic extension back legs, and automatic extension foot rest are pivotally connected to work together and which are controlled by a single lever.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:-

Figure 1 represents a side elevation of a chair constructed in accordance with this invention the chair being shown in upright position in full lines and in its extreme lowered position in dotted lines in which latter position it forms a couch;

Fig. 2 is a longitudinal section of the chair opened up for use as a couch;

Fig. 3 is a transverse section taken on the line 3-3 of Fig. 2;

Fig. 4 is a front elevation of the chair in couch position;

Fig. 5 is a detail sectional view showing a part of the locking mechanism; and

Fig. 6 is a detail perspective view of the crank rod used in connection with the locking mechanism.

In the embodiment illustrated a seat frame 1 is shown supported by a pair of front legs 2 and rear legs 3, the front legs being connected by a cross bar or plate 4 and the rear legs 3 by a similar plate or bar 5.

A back 10 has side bars 11 pivotally connected at their lower ends to the rear portion of the seat 1 at the sides thereof and at points spaced above said pivotal connection. These side bars 11 are provided with laterally and forwardly extending lugs 12 to the front ends of which are pivotally connected the rear ends of the arms 13. The front ends of these arms 13 are pivotally connected with the members 14 which are cut away to receive the upper ends of the bars 17 that are secured thereto. The lower ends of the bars 17 are connected by the bar 18 and provide a supporting frame for the apron frame 20 to be hereinafter more fully so descr bed.

A pair of rear extension legs 30 the individual legs of which are connected by a rod 31 and a cross bar or plate 32, are pivotally connected at their upper ends to the lugs 12 as shown at 16. The cross member 32 which connects the sections of the extension legs 30 is L-shaped in cross section as shown in Fig. 2 and has pintles 33 at the ends thereof journaled in the leg sections so that said member 32 may pivot when the leg section is moved into and out of operative position.

A bar 34 is fixedly connected at one end to the member 32 and has a roller 35 mounted on the lower face of the free end which is designed to travel on a platform or board 36 which extends longitudinally of the chair below the seat. This bar 34 has fixed to its upper face a longitudinally extending rack bar 37 with the teeth of which is designed to be engaged a crank shaft or rod 38 journaled in the sides of the seat frame as is shown clearly in Fig. 3. This rod 38 is provided with fingers 39 at its opposite ends which are positioned for con-

venient grasping by the occupant of the chair to release the rod from the rack bar when desired and yet is completely concealed.

- 5 A cross bar 40 is arranged transversely of the back of the chair back 10 at a point about midway the length thereof and when the back is swung into its extreme lowermost position as shown in Fig. 2 this bar 40 rests 10 on the member 32 carried by the extension leg 30 providing a solid base for the back of the chair to rest on. When the chair back 10 is in its horizontal position as shown in Fig. 2 the leg supporting apron frame 20 at 15 the front end thereof is also in alinement therewith and the chair becomes a couch firmly supported by six legs.
- 10 The free ends of the bars 17 overlie the side members 21 of the apron frame 20. 20 The side members 21 are longitudinally grooved on their inner faces as shown at 22 in which an extension 23 is designed to reciprocate, said grooves forming tracks for the extension.
- 25 The apron frame 20 is pivoted to the front end of the chair seat by the same bolts shown at 15 that support the members 14. These bolts operate as axes on which the front posts or links 14 work like levers on 30 a fulcrum.

The supporting frame for the apron frame may be raised to a position corresponding to that of the back of the chair and this movement of the said frame lifts with it in its upward movement by means of a bar 18 the apron 20, now to be described.

The side members 21 of the apron frame 20 have their upper ends pivotally connected with the chair seat frame by means of the bolts 15, said lower portions being located within the bars 17. These side members 21 are longitudinally grooved as shown at 22 on their inner faces to form guides for the sliding extension 23. A cross bar 24 connects the lower ends of the frame members 21 and against which the cross bar 18 is designed to rest when the apron is in raised position and the chair lowered to form a couch as is shown clearly in Fig. 2.

50 Brackets 25 are secured to the inner faces of the members 21 near their inner or upper ends as shown clearly in Fig. 2 and these brackets are designed to support rack bars 26 pivoted at one end to the brackets 25 and which extend rearwardly under the chair seat with the teeth thereof extended downwardly and designed to engage the upper ends of angle bars 27 which are fixed to the cross bar 4 at opposite sides of the 55 chair. Links 28 are pivoted at one end to the lower end of the angle bars 27 and at

their upper ends to one corner of substantially triangular shaped levers 29 another corner of which is pivoted to brackets 25 as shown at 41. The other corners of the triangular levers or plates 29 are pivotally connected with hinge members 42 which are here shown provided with right-angular apertured ears 43 pivoted to the plates 29. The upper ends of the hinge members 42 are hingedly connected with the inner ends of the apron extension 23.

60 A rod 44 extends transversely across the seat frame at the front thereof and is rotatably mounted in brackets 45 carried by the frame. This rod 44 is equipped at its ends with right-angular fingers 46 and carries lugs 47 which are located beneath the rack bars 26 carried by the apron frame so that the rods may be turned to bring these lugs into engagement with the rack bars and elevate them to release them from the upper ends of the angle bars 27 and permit the apron to drop down into lowered position.

65 The apron 20 may be raised and lowered independently of or simultaneously with the chair back, it being frequently desired to raise the apron to support the user's legs when the chair back is in upright position and this is accomplished by lifting the apron which causes the rack bars to slide over the angle irons or bars 27 until the apron reaches the desired height when the release thereof will cause the bars to engage the angle irons and lock the apron in adjusted position. The 70 raising of the apron beyond a predetermined point causes the sliding extension 23 to move outwardly owing to the lever and link connection between it, the angle bars 27 and the brackets 25.

75 I claim:

A chair including a seat frame, a back rest pivotally connected with the seat frame, a forward extension pivotally supported on the seat frame, a board secured under the seat frame and having an exposed upper surface, extension legs pivotally connected with the back rest, pintles on the extension legs, a bar pivotally mounted on the pintles and having a roller on its inner end, said 80 roller adapted to move over the board to support the inner end of the bar, a rigid member carried by the bar and adapted to move to a position under the back and to engage the back rest and support the back rest in a horizontal position, and means for simultaneously moving the forward extension.

85 In testimony that I claim the foregoing as my own I have hereto affixed my signature.

LEWIS W. PARSONS,
